MARINE TRANSFER RAMP

William A. Pitts and Campbell M. Carothers,
Houston, Tex., assignors, by mesne assignments,
to Standard Oil Development Company, Eliza-
beth, N. J., a corporation of Delaware

Application June 26, 1948, Serial No. 35,424

1 Claim. (Cl. 14—71)

This invention relates to an improved transfer ramp which is particularly adapted for connection with a moving object of variable elevation such as for making connection between a stationary dock or platform and a moving boat.

An object of the present invention is to provide means for making such connection particularly for transfer of personnel in which a minimum of relative motion between adjacent parts occurs at all points throughout the transfer. These and other objects of the present invention will be apparent from the following description and the drawings.

Fig. 1 of the drawings is an asymmetric view of an illustrative embodiment of the present invention;

Fig. 2 is a diagrammatic view in elevation of a second modification of this invention designed for use over a wider range of elevation;

Fig. 3 is a detailed view in partial section of the device for connecting the ramp with the deck of the boat, while

Fig. 4 is a detailed asymmetric view of a suitable device for connecting the other end of the ramp with a platform or deck.

Referring to the figures in greater detail, the ramp consists of a walkway 1 surfaced with any suitable strong but lightweight material, such as expanded metal, and a small rigid ladder 2. The walkway 1 is supported at one end pivotally on crossbar 3 which is rigidly attached to the surface of a flanged pin 4. This pin fits into a recess 5 in the surface of the platform 6 thereby permitting motion of the walkway circumferentially (in a substantially horizontal plane) about the axis of the pin 4 and also vertically about the axis of the bar 3 but preventing tilting of the walkway sideways about its own long dimension. The ladder 2 is connected to the other end of the walkway 1 by hinged connections 7 which also serve to prevent the ladder 2 from tilting sideways by permitting its free motion pivotally with respect to the outer end of the walkway.

Provision for connection with the deck of a boat is provided by the ball point 8 attached to the lower end of the ladder 2, the two sides of the ladder being joined in this ball. The ball is preferably of hard rubber or other tough plastic material to avoid damage to the boat. Connection may be made with the boat deck simply by lashing the end of the ladder against a suitable deck cleat 9 but a preferred connection is to provide a hemispherical cup 10 rigidly affixed to the deck and to hold the ball 8 in this cup

by a suitable lashing with rope 11 to one or more cleats 29 on cup 10.

The walkway may also be provided with side rails 12 and with suitable diagonal bracing for strength. It is also desirable to provide hoisting means such as line 13 attached to the walkway for raising and lowering it as by means of a suitable counterweight 15 which normally supports the ramp assembly in a balanced condition. This cable 13 is preferably connected as illustrated to a point above the walkway 1. This connecting point should be selected so that the walkway structure exerts a substantially uniform pull on the cable 13 throughout the entire range of elevation of the walkway, thus permitting uniform action of the counterweight in all positions.

Referring to Fig. 2, one or more additional extension ramps 16 provided with a separate hoisting line 17, and winch 18 may also be provided to extend the range and flexibility of the device. In this arrangement the large heavy ramp 16 is preferably connected pivotally to the dock 6 by hinge 21 so that it moves only in a vertical arc and the connection between the lighter ramp or walkway 1 and ramp 16 is similar to that illustrated in Figs. 1 and 4, the pin 4 being set rotatively about its axis in a recess in a rigid end member of the ramp 16. However, both the connections to the dock 6 and between the ramps 1 and 16 may be of the pivoted pin 4 type or the dock connection may be of the pivoted pin type and the two ramps may be connected by a hinge. Additional ramp units may be suitably added as needed.

In the operation of this device the boat is preferably first moored by mooring line 20 to the platform with a suitable length of line permitting the ladder 2 to be lowered onto the deck at a point approximating the cup 10. Then, while maintaining tension on mooring line 20, the ramp is lowered by pulling on ladder 2, the ball point 8 is directed into the cup 10 and the lower end of the ladder is firmly lashed to cleats 23.

This connection thus gives approximately point contact between the boat and the ladder thus reducing the movement and stresses imparted to the ramp by the motion of the boat. This arrangement allows the boat to roll and pitch with very little relative motion of the ladder and makes it possible for personnel to ascend or descend the ladder 2 and one or more ramps 1 and 16 with little danger of falling into the water or being injured by suddenly moving parts of the equipment. This is because there is very

little relative motion between any adjacent parts at any point throughout this device even though the boat may be rolling and pitching in a rough sea. This permits a man using the device to adjust himself to the observed pitch and yaw of the boat without encountering unexpected contrary motion of parts of the ramp.

While the invention has been described with reference to the specific device as illustrated in the drawings and in its particular application to a connection between a small boat and a stationary platform, it is obvious that many variations in these specific elements and their uses may be made without departing from the spirit of this invention. For example, the higher platform 6 may represent the deck of another boat, usually a relatively larger boat, and the device may thus be used for transferring between two vessels at sea, or between a large boat and a stationary or floating dock or barge. The invention is also not limited to the specific types of winches and counterweights shown for there are many obvious variations for raising, lowering and counterbalancing the ramps.

It is claimed:

A ramp structure for connection between marine structures subject to relative movement one to another, comprising in combination, a substantially rigid walkway platform having an inboard end and an outboard end, a relatively rigid support for the inboard end of said platform consisting of a cross bar element extended laterally of said platform in journalled engagement therewith and a pivot pin secured to said cross bar element at the midpoint longitudinal-

ly thereof in rigid, right angular relation thereto, said pin engaging a corresponding socket carried by one of said marine structures, a flexible support for the outboard end of said platform, consisting of a ladder unit, including longitudinal side rail portions, said unit having an inboard end and an outboard end, a transverse pivoted joint between the inboard end of said ladder unit and the outboard end of the platform, said ladder side rail portions at the outboard end thereof extended angularly inward to a rigid junction at a midpoint therebetween, and a ball-type terminal element substantially integral with said rail portions at said junction, a socket member receiving said terminal element and connected to said other marine structure, means for securing said terminal element and socket against separation, and means for substantially counterbalancing the weight of said platform.
